195,882

COMBINED CIGARETTE PACKAGE AND MATCH BOOK DISPENSER

William H. Penney, 15 Putnam St., Revere, Mass.

Filed Feb. 1, 1962, Ser. No. 68,608

Term of patent 14 years

(Cl. D52—2)

FIG. 2

FIG. 1 is a front perspective view of a combined cigarette package and match book dispenser; and FIG. 2 is a rear perspective view thereof.

The undisclosed side of the dispenser is substantially the same in appearance as the side shown.

I claim:

The ornamental design for a combined cigarette package and match book dispener, as shown and described.
